Frank M. Vogan, Canton, Ohio, assignor to The Reeves Manufacturing Company, Dover, Ohio, a corporation of Ohio

Application October 15, 1936, Serial No. 65,307

Term of patent 14 years

To all whom it may concern:

Be it known that I, Frank M. Vogan, a citizen of the United States, residing at Canton, in the county of Stark and State of Ohio, have invented a new, original, and ornamental Design for Ceiling Panels, of which the following is a specification, reference being had to the accompanying drawing, forming part thereof.

Figure 1 is a plan view of a ceiling panel, showing my new design; and

Fig. 2, an enlarged sectional view on the line 2—2, Fig. 1.

I claim:

The ornamental design for a ceiling panel, as shown.

FRANK M. VOGAN.
